CLAIM

The ornamental design for a wine bottle, as shown and described.

DESCRIPTION

This application is related to co-pending U.S. design application Ser. No. 29/342,342 filed Aug. 23, 2009 to the instant inventor.

FIG. 1 is a side view of a wine bottle showing my new design;

FIG. 2 is a front view thereof; and,

FIG. 3 is a perspective view thereof.

The broken line showing the pour spout, bottle neck, top portion of a bottle and bottom of a bottle is included for the purpose of illustrating only and forms no part of the claimed design.

The present invention relates to an ornamental design for a wine bottle.
